UNITED STATES PATENT OFFICE.

EDWARD M. STEPHENSON, OF HARTFORD, CONNECTICUT.

SPRAY TANK.

Application filed September 29, 1922. Serial No. 591,255.

To all whom it may concern:

Be it known that I, EDWARD M. STEPHENSON, a citizen of the United States, residing at Hartford, in the county of Hartford and State of Connecticut, have invented a new and useful Improvement in Spray Tanks; and I do hereby declare the following, when taken in connection with the accompanying drawing, and the characters of reference 10 marked thereon, to be a full, clear, and exact description of the same, and which said drawing constitutes part of this application.

This invention relates to an improvement in spray tanks. In coating small articles, such 15 as buttons, buckles, clasps, etc., with an enamel or other similar material, the articles are arranged in trays, and the coating is applied by means of a spray gun, but a comparatively large proportion of the coating 20 material does not fall on the articles to be coated, and hence is wasted. The object of this invention is to provide a tank to contain the coating material and over which the articles to be coated are placed, so that 25 the coating material which does not adhere to the articles may fall back into the tank, and the invention consists in the construction as hereinafter described and particularly recited in the claim.

30 A perspective view of a spray tank constructed in accordance with my invention is shown in the drawing.

In carrying out my invention, I employ a tank 5 of any suitable size and dimensions. In the bottom of the tank is an outlet 6 connected by a tube 7 with a spray gun

8 of any approved construction. Over the outlet 6 is placed a cup-like strainer 9. In one side of the tank, near the upper edge, is an opening 10 to an exhaust pipe 11 40 through which fumes from the tank may be drawn. Preferably, a door 12 will be provided to close the opening 10. The buttons 13, or other articles to be coated, are placed upon trays 14, and these trays are 45 placed upon a rack 15 adapted to rest upon the upper edge of the tank, which is partly filled with the coating material. The articles to be coated are sprayed in the usual way and all surplus coating material will 50 fall back into the tank, and consequently is saved. The strainer prevents any foreign matter from escaping into the spray gun. I thus provide, in a very simple way, 55 means for coating small articles by spraying but avoiding the waste of coating material.

I claim:

The combination with an open spray tank provided in its bottom with an outlet, a 60 strainer over said outlet, a tube connected with the lower end of said outlet, a spray gun connected with said tube, and a rack supported upon the upper edge of said tank.

In testimony whereof, I have signed this 65 specification in the presence of two subscribing witnesses.

E. M. STEPHENSON.

Witnesses:

MALCOLM STEPHENSON,
FREDERIC C. EARLE.
